JAMES NORMAN HARRIS, OF QUEENS VILLAGE, NEW YORK

APPARATUS FOR DISPLAYING RUGS AND THE LIKE

Application filed November 9, 1929. Serial No. 405,917.

The primary object of my invention is to provide an apparatus for showing or displaying floor rugs. However, my invention can be used for showing draperies, linens, and other like flexible articles as well, as will be observed.

The nature of my invention will be understood from the accompanying drawings and the following description of a machine embodying it. In the accompanying drawings: Fig. 1 is a vertical section of the machine, shown in perspective in Fig. 6, and about on the line I—I of Fig. 2. Fig. 2 is a front elevation of the working apparatus, the case or cabinet containing the same being in section. Fig. 3 is an enlarged detail, showing one rug being taken away from display position and another brought into view. Fig. 4 is a detail on line IV—IV of Fig. 3. Fig. 5 is a sectional detail on line V—V of Fig. 1. Fig. 6 is a perspective of the machine, showing a rug at rest on display at the window in the case or cabinet thereof.

For the smaller floor rugs at least, the working parts of the apparatus can be conveniently enclosed in a case or cabinet 1, through a window 2 of which the rugs are shown successively, as illustrated in Fig. 6.

A number of carrier rods 5 are provided, usually one for each rug of the stack or group to be exhibited; these carrier rods may be solid or hollow, and each is of somewhat greater length than the length or breadth of the rugs 6 to be shown; with relatively long rods and short or narrow rugs however, each rod may serve for two or more rugs. The rugs are hung from these rods. Metal straps 7, encircling the rods in individual circumferential grooves 8 and having their ends fastened to the rugs by pins or removable rivets 9, are suitable and convenient means for hanging the rugs on the rods. Longer rugs may be folded over the rods. A pair of spaced elongated supports 12, on which the two ends of each of the rods rest, support the group of carrier rods 5 at such a height above the floor that the rugs 6, hanging downwardly between the supports 12, are substantially suspended from the rods as illustrated in Figs. 2, 3 and 6. The rods, with their

rugs, are to travel toward the front or window 2 on these supports as the foremost rods and rugs are removed successively. For this purpose, the supports 12, in the form of rails, are preferably inclined toward the front or window 2, so that gravity may move the rods and rugs in the desired direction, the ends of the rods sliding or rolling on the rails. The latter may be carried by suitable brackets, such as 13 for example, hung on the walls 10 of the case or cabinet 1. If desired, further supporting rails 14 for the rods may be located farther from the ends of the rods and these can be carried by extensions from the previously described bracket or brackets 15 carried by the rails 12. Stops, such as the stops 18, one at the lower end of each of the rails 14, prevent the rods rolling or sliding off the lower ends of the rails. The rails, or the ends of the rods engaging with the rails, may or may not be provided with anti-friction devices to promote ready movement of the rods along the rails; for small rugs at least the bare round ends of the rods seem sufficient. The rug on the rod which is for the moment the lowest or foremost, is the rug on display, and in such a cabinet as here illustrated is seen through the window 2; the remainder are concealed behind this rug on display (Fig. 6). Placed substantially above the rails 12 and hence rather close to the group of carrier rods 5, another support or supports for the rods extends or extends from the lower ends of the rails 12 to beyond the upper ends of the same, as shown particularly in Fig. 1. Like 12, this supporting device or mechanism may be a pair of spaced rails 20, and they may be carried by brackets on the side walls of case 1. From the lower ends of the rails 12 and 14, a pair of belts 19, of equal lengths and preferably chain belts, successively transfer the lowermost or foremost carrier rod to the support or supports 20, and thereon convey it to the rear with its rug trailing behind it. The belts move in the direction of the arrow 23 in Fig. 1. To engage the rods, each belt is provided with a projecting member 21, rigidly fixed to the belt in projecting position; the two members 21 are arranged op

posite each other (Fig. 2), and each consists of a pair of long and short fingers. As the movement of the belts brings this pair of members to the foremost or lowermost rod, 5 the long fingers of these members pick up the two ends of that rod simultaneously and deposit them on the lower end of the supports 20. It will be observed that the upper finger of each member 21 is shortened so as to pass 10 the foremost carrier rod 5 (Fig. 2), while the lower finger is long enough to engage underneath this foremost carrier rod and lift it on to the supports 20; each member 21 receives the rod between its fingers therefore. The 15 lower ends of the two upper supports or rails 20 may be bent downwardly as indicated at 24 to receive the ends of the rods almost as soon as they leave the rails 12 and retain the rods between the fingers as the finger members 21 20 turn it face downwardly in passing over the pulleys or sprockets 25 (Fig. 3). One of these pulleys or sprockets 25 is provided for each chain belt near the lower ends of the adjacent rails 12 and 20, as appears in Fig. 25 1, while another pulley or sprocket 26 is provided near the upper end of each rail 20. Each belt 19 passes directly from pulley 25 to pulley 26 at the same side of the apparatus, and these two pulleys are so placed that the 30 upper runs of the belts 19 (i. e. from 25 to 26) are substantially parallel to the upper rails 20, and everywhere are so close to these upper rails that these rails retain the rods in the finger members 21, as shown in Fig. 3, until 35 the latter begin to pass around the pulleys or sprockets 26. Hence the belts 19, moving in the direction of the arrow 23 (and the two belts travelling at equal speeds) not only serve to lift the rod on to the upper supporting rails or members 20, but also to slide or roll the carrier rods up these rails 20 to the sprockets 26. As shown in Figs. 1 and 3, the 40 pulleys or sprockets 25 are so located preferably, that the line of their axes passes very close to the lower ends of the rails 14; these sprockets themselves then, or the tension on the belts in passing around these sprockets, serve to hold the members 21 with their fingers projecting properly to lift the rods 45 from the lower to the upper rails. Chain guides 29 and 30, on brackets fastened to the cabinet's walls, may be provided on both sides of these runs of the belts to hold the same against flexing by gravity or under the 50 strain of dragging the rod and its rug along the rails 20, the upper of these guides serving particularly to hold the members 21 depressed in contact with the rod they are at 55 the moment moving along these rails. The rug attached to the particular rod 5 being moved on these upper rails 20, flexes as indicated in Fig. 3, and trails behind its rod; if nothing on which this rug may slide is 60 provided above the group of rods 5 left on

the lower rails 12, the rug is simply pulled directly across these rods.

From the pulleys 26, the carrier rods 5 and their rugs are to be replaced on the upper ends of the lower rails 12, behind the rods and 70 rugs remaining on the lower rails. In order to pull each rug around the line of the axes of the sprockets 26, or at least to pull them far enough around the line of these axes for the trailing ends of the rugs to fall by their own 75 weight below their respective rods again, I run the belts 19 more or less downwardly from 26 and then upwardly to the rear ends of the rails 12. Thus as the carrier rods 5 reach the pulleys 26, they are carried from 80 thence downwardly to the pulleys or sprockets 31. In these downward runs of the belts, the belts are held against flexing by the vertical guides 32 and 33, which also are carried from the side walls of the case or cabinet 1 by brackets. From the pulleys 31, the belts run upwardly to the pulleys or sprockets 34 for the delivery of the bars on to the rails 12 and 14; similar guide plates 35 and 36 hold these upwardly-travelling runs of the belts against 85 flexing. Rod-guiding plates 38, mounted like the other guide plates are arranged to receive, against their vertical rear edges 37, the carrier rods 5 as the latter pass over the pulleys or sprockets 26 and hold the rods against 90 escape from between the finger members 21 as the latter draw the rods down toward 31; in Fig. 1, this rear edge 37 lies directly behind the lefthand run of the belt 39, but is shown in Fig. 5. Adjacent the pulleys 26, a 95 guide 40 may be provided for the rugs themselves around which they will turn downwardly; this may be simply the axle on which the pulleys 26 are mounted, or a larger guide may be used for the heavier and larger rugs. 100 As the rod 5 is drawn downwardly therefore, it draws its rug behind it around 40, until (either before or after the rod passes around the pulleys 31) so much of the rug has passed around the turning point 40 that it falls by 105 its own weight. The belts 39, mounted on pulleys on axles 40 and 42 (the latter being the mounting for pulleys 31) serve as guides to assure that the falling end of the rug falls rearwardly, that is to say, in a direction away 110 from the lower ends of the rails 14. The forward edge 41 of guide plate 38 is so placed as to receive the rod as the latter passes around the axis of pulleys 31 and confine the rod in the finger members 21 in the upward runs of 115 the belts 19, and until these finger members turn to face upwardly in passing around the sprocket 34. The manner in which the guide plate 38 confines the rod ends in the finger members 21 is illustrated in the lower left-hand portion of Fig. 1. 120

As the pair of finger members 21 passes over the sprockets 34 and turns downwardly, the rod 5 between their fingers is permitted to slide or roll out of the fingers. These pulleys 125 130

or sprockets 34 are located with their axes near the rear (or lefthand) ends of the rails 12 and 14, and at such an elevation that the rods 5, in passing out from between the fingers 5 of 21, slide or roll on to the rear ends of these rails. From thence each carrier rod slides or rolls down the rails until stopped by the carrier rods ahead of them. The rug attached to the carrier rod thus replaced on the rail 10 again becomes one of the group awaiting showing at the lower ends of the rails. The belts 19 continuing their travel in the direction of the arrow 23, the pair of finger members 21, now empty, are again brought to the 15 lower ends of the rails 12, and the action just described is then repeated on the next rug, this second rug being taken away and replaced on the rails 12 and 14 behind all the rest, while the third rug is being shown through the 20 window. Obviously continued repetitions of these operations will bring every rug to displayed position in its turn, and obviously the whole group of rugs may be run through as many times as desired.

25 While I have described the use of but one pair of finger members 21, it will be obvious that more than one pair may be employed if the belts 19 are sufficiently long. If, for example, each belt is a little more than twice the 30 length of the longest rug, two pairs of members 21 may be used, these acting on alternate rugs.

Individual idler pulleys or sprockets 45, one for each chain belt, are mounted on adjustable slides 46 to permit tensioning of the 25 belts as desired.

As before stated, the two belts 19 are to be driven at equal speeds. For this purpose, both the pulleys 26 are fastened to the shaft 40, which is made the driving shaft. Preferably, I arrange to drive the apparatus electrically and, for this purpose, I have provided an electric motor 45, which acts through a speed-reducing mechanism 46 and 45 chain belt 47 to drive the shaft 40 as illustrated. Preferably I interpose a friction or slip clutch 43 between the shaft 40 and the sprocket thereon driven by the chain belt 47, to prevent damage in the event that 50 the free movement of one of the belts 19 is interfered with; this limits to a safe value the driving strain that the motor can put on shaft 40. To readily control the successive transfer of the rugs from front to back, I 55 carry the energizing circuit 44 (see Fig. 1) of the motor 45, through a switch 49 located adjacent one of the belts 19, the arm 48 of which is thrown manually to closed position by the operator pushing in the sliding bar 50; 60 a spring 51 tends to pull this sliding bar 50 outwardly again and hence open a switch to stop the motor, but a hook 52, acting under the pull of the spring 53, ordinarily holds the sliding bar 50 in switch-closed position when 65 once placed in that position. The projecting

end 54 of the hook 52 is so placed in the path of the finger member or members 21 of the adjacent belt 19 however, that when a pair of these finger members approach the lower ends of the rails 12 and 14 to pick up a carrier rod 5, the projecting end 54 of the hook 52 is struck and raised against the pull of the spring 53 (the hook 52 turning on the pin 55). This lets the spring 51 act to pull the rod 50 towards the right in Fig. 1 and open the motor circuit, stopping the movement of the belts 19. When the operator desires to take away the rug which is on display for the moment, to show the one behind it, he simply pushes the sliding rod 50 inwardly again. If the operator desires the machine to operate continuously, taking away the foremost rugs one after the other without attention on his part, he turns the button 56 while the sliding rod 50 is in its switch-closing position. This engages the inner bent end of 57 in the notch of bar 50. Obviously lifting of the latch 52 does not serve to open the switch so long as the button is in this notch. An upper sliding bar 58, 85 having a cam near its lefthand end, is arranged to pass underneath and lift the latch 52 when pushed inwardly. This permits the operator to stop the machine at any time and with a rug or rugs in any position of displacement.

It will be understood that my invention is not limited to the details illustrated and described except as appears hereinafter in the claims.

I claim:

1. In an apparatus for displaying rugs and the like, a pair of spaced elongated supports, a plurality of carrier rods for the rugs or the like to rest at their ends on said supports, said supports being located at such a height that the said articles carried by the rods can be substantially suspended from the rods, supporting means for the rods located immediately above said pair of elongated supports and extending from substantially one end of each of said pair of supports to substantially the opposite end thereof, a pair of belts respectively adjacent said pair of supports for successively transferring the foremost of said carrier rods from said pair of supports to said supporting means, moving the same, supported by the latter, to adjacent the opposite ends of said pair of supports, and there replacing the carrier rods on the pair of supports, and pulleys supporting said belts, including a pair of pulleys the line of the axes of which passes close to those ends of said elongated supports from which the carrier rods are transferred to said supporting means.

2. In an apparatus for displaying articles such as rugs and the like, a pair of spaced parallel rails, a plurality of carrier rods for the articles to rest at their ends on said rails,

said rails being located at such a height that the articles carried thereby can be substantially suspended from the rods and being inclined so as to cause the rods to move thereon toward one end of the rails, supporting means for the rods located above said rails, a pair of belts located respectively adjacent the rails to successively transfer the carrier rod at the lower ends of the rails to said supporting means, move the same, supported by said means, toward a position above the upper ends of the rails, then move the carrier rods downwardly to a position lower than the upper ends of the rails, and then upwardly to replace the rods on the rails at the upper ends thereof, and belt guides to hold the belts against flexing at said downward and upward runs thereof.
